WRINGER AND THE LIKE

Walter L. Kauffman, II, Erie, Pa., assignor to
 Lovell Manufacturing Company, Erie, Pa., a
 corporation of Pennsylvania

Application October 5, 1939, Serial No. 298,098

7 Claims. (Cl. 68—263)

Wringers and the like are commonly provided with some form of safety device making the indrawing action of the rolls under pressure inoperative in case of accident. Such safety devices, of course, must be quick acting in order to avoid very serious injury and should be so easily operated as to be effective under panic conditions.

The present invention is designed to improve the manner of operating the safety device in order that the effort to effect a safety action may be delivered in a variety of directions and thus add to the certainty of effective operations in the operation of the safety mechanism. The invention is exemplified utilizing a safety device which releases the pressure on the rolls. Features and details of the invention will appear from the specification and claims.

A preferred embodiment of the invention is illustrated in the accompanying drawing as follows:

Fig. 1 shows a front elevation of a wringer, partly in section.

Fig. 2 an end elevation of a wringer.

Fig. 3 a section on the line 3—3 in Fig. 2.

Fig. 4 a section on the line 4—4 in Fig. 3.

Fig. 5 a section on the line 5—5 in Fig. 3.

The wringer frame, as shown, has a base 1, side stiles 2 and 2a, and a top member 3. Rolls 4 and 5 are mounted in the frame, these rolls having shafts 6 and 7 respectively, the shaft 6 forming the driving means for the lower roll, the upper roll being driven from the lower roll. The shaft 6 is journaled in bearings 8 arranged in the side stiles and resting on the base. The shaft 7 has bearings 9 slidably mounted in the stiles. A spring 10 operates on the bearings 9. The pressure of the spring is adjusted by a screw 11 arranged on the top member 3.

An interlocking connection is provided at 12 between the top member and the lower member in a well known manner providing means for detachably securing this end of the top member to the lower part of the frame. A resetting lever 13 is hinged at 14 at the opposite end of the wringer. The resetting lever is connected by a link 15 with the frame, completing a toggle connection. One end of the link is connected to the lever 13 by a pivot 16. The opposite end of the link is connected by a rod 17 with a channel plate 18. The channel plate is secured to the face of one of the stiles. The link 15 is U-shaped having two flanges, one at each side of the channel.

A trip rod 19 extends fore and aft through a

cam opening 20 in the channel piece 18 and through a cam opening 21 in the side walls of the lever 13, the lever 13 being of channel form. Handles 22 are mounted at each end of the rod, these handles having cam surfaces 23 which are adapted to engage the corners of the stile. The rod 19 also has a bend 25 which may be thrown out of the plane of the connecting web of the channel plate 18 by a rotative movement of the

10 trip rod.

The pivots of the lever 13 are slightly out of line, making the setting of the lever slightly stable. When it is desired to release the pressure on the rolls, the rod 19 may be operated through the handles 22 by a pressure exerted on these handles in any direction, that is to say, forward or back, up or down, or crosswise, or rotatively, or combinations of these movements. This is accomplished as follows:

20 If the handle 22 is moved up or down, the rod 19 operating on the cams 20 and 21 push the rod outwardly, and as it is always against the edge of the cam 21, this moves the lever outwardly into unstable position and effects a release.

25 Should the handle 22 be moved outwardly, that is, away from the wringer, the opposite end of the rod would operate as a fulcrum and the rod, operating against the cam surface of the slot 20 would operate on the cam 21 and move the lever outwardly and effect a release.

30 Should the handle be moved toward the wringer, the rod fulcrumed in the bottom of the slot 20 would move the opposite end of the rod outwardly and effect a release. If the rod is moved inwardly, the same surfaces 23 arranged on the handle 22 engaged by the operator, operate on the corners of the stile and move, through the pressure of the rod 19 with the cam notch 21, the lever outwardly and effect a release.

35 40 On the other hand, if the handle is pulled toward the operator, the camming action of the opposite handle will force the rod outwardly and effect a release.

Again, if the rod is rotated in either direction, 45 the deflections or bends 25 will engage the channel piece 18 and will throw the rod outwardly carrying with it the lever through engagement with the edge of the cam slot 21, one deflection of the bend 25 being effective for this purpose 50 when the handle is turned in one direction and the other deflection of the bend when the handle is turned in the opposite direction.

It will be seen, therefore, that this device is operative through universal action, that is, it may be moved in any direction, push or pull, up

or down, in or out, and also by a rotative movement in either direction, and in all cases effect a release. Thus if the handle is operated by the operator in any way, it effects a release and this is important under the panic conditions in which the operation is performed.

What I claim as new is:

1. In a wringer or the like having a frame, rolls mounted in the frame, pressure and driving means for the rolls, the combination with the pressure and driving means of a safety means rendering wringing action of the rolls ineffective, comprising an operating member constructed and arranged to act in response to pressure in any and all directions making said safety means effective. 15

2. In a wringer or the like having a frame comprising top and bottom members, rolls mounted in the frame, and a pressure means exerting pressure from the top member on the rolls comprising a toggle connection between the top member and bottom member, the combination with the pressure means of a safety means comprising a trip rod operating on the toggle to release the pressure on the rolls, said trip rod being responsive to pressure on the rod from front to rear and sidewise relatively to the front and rear direction of movement of the rod and constructed and arranged to act on the toggle to effect a release through breaking of the toggle. 20

3. In a wringer or the like having a frame comprising top and bottom members, rolls mounted in the frame, and a pressure means exerting pressure from the top member comprising a toggle connection between the top member and bottom member, the combination with the pressure means of a safety means comprising a trip rod operating on the toggle to release the pressure on the rolls, said trip rod being constructed and arranged to be responsive to pressure on the rod from front to rear and rotatively about the axis of the rod to effect a release through breaking of the toggle. 35

4. In a wringer or the like having a frame comprising top and bottom members, rolls mounted in the frame, and a pressure means exerting pressure from the top member on the rolls

comprising a toggle connection between the top member and bottom member, the pivots of the toggle being arranged to form a stable set position of the toggle, the combination with said toggle connection of a rod extending from front to rear and having camming engagement in relation to the frame and toggle to actuate the toggle to release position by an endwise movement and fulcrumming on the frame to move the connection to release position by a movement of the rod laterally relatively to the direction of forward and back movement of the rod, the rod having laterally extending parts effecting a movement of the connection to release position by rotative movement of the rod. 5

5. In a wringer or the like having a frame, rolls mounted in the frame, and pressure means for the rolls, the combination with said pressure means of a safety means rendering wringing action of the rolls ineffective comprising an operating member constructed and arranged to act in response to pressure in any and all directions for releasing the pressure means. 10

6. In a wringer or the like having a frame, rolls mounted in the frame, pressure and driving means for the rolls, the combination with said means rendering wringing action of the rolls ineffective of a safety means comprising a member mounted to rotate about an axis of rotation extending from front to rear of the wringer and to move with said axis laterally of said axis and constructed and arranged to respond through said movements in making said safety means effective. 25

7. In a wringer or the like having a frame, rolls mounted in the frame, pressure and driving means for the rolls, the combination with the pressure and driving means of a safety means rendering wringing action of the rolls ineffective, comprising a trip rod extending in a direction from front to rear of the wringer frame, said rod being mounted to rotate about an axis extending from front to rear of the wringer and to move with said axis laterally of said axis and constructed and arranged to respond through said movements in making the safety means effective. 40 45
